US00D845686S

(12) **United States Design Patent** (10) **Patent No.:** **US D845,686 S**
Mandon et al. (45) **Date of Patent:** **** Apr. 16, 2019**

(54) **DISPLAY STRUCTURE**

(71) Applicant: **Apple Inc.**, Cupertino, CA (US)
(72) Inventors: **Kully Kraig Mandon**, San Francisco, CA (US); **Casey Feeney**, Los Gatos, CA (US); **Jean-Marc Gady**, Los Gatos, CA (US); **Bridget Cinquegrano**, San Francisco, CA (US)

(73) Assignee: **Apple Inc.**, Cupertino, CA (US)(**) Term: **15 Years**(21) Appl. No.: **29/593,108**(22) Filed: **Feb. 6, 2017****Related U.S. Application Data**

(63) Continuation of application No. 29/522,930, filed on Apr. 3, 2015, now Pat. No. Des. 778,087.
(51) **LOC (11) Cl.** **06-04**
(52) **U.S. Cl.**
USPC **D6/702**

WO DM041938 10/1997

Primary Examiner — Ricky Pham*(74) Attorney, Agent, or Firm* — Sterne, Kessler, Goldstein & Fox P.L.L.C.(57) **CLAIM**

The ornamental design for a display structure, as shown and described.

DESCRIPTION

FIG. 1 is a top right front perspective view of a display structure showing the claimed design;

FIG. 2 is a bottom left front perspective view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The dot-dash lines in the figures show boundaries that form no part of the claimed design.
